(Cl. D52—1)

To all whom it may concern:

Be it known that I, Edward C. Gillett, a citizen of the United States, residing in Evanston, in the county of Cook, State of Illinois, have invented a new, original, and ornamental Design for a Span Measuring Device for Bowling Balls and the Like, of which the following is a specification, reference being had to the accompanying drawings, forming a part thereof.

Fig. 1 is a perspective view of a span measuring device for bowling balls and the like embodying my new design;

Fig. 2 is a side elevation thereof;

Fig. 3 is an end elevation;

Fig. 4 is a top plan view.

I claim:

The ornamental design for a span measuring device for bowling balls and the like, substantially as shown.

EDWARD C. GILLETT.
